CLAIM

We claim the ornamental design for: finial, as shown.

DESCRIPTION

FIG. 1 is a side elevation of our new design for: finial with FIG. 1 showing all side elevations of our design, including front, opposite sides and rear.

FIG. 2 is a top plan view of the device shown in FIG. 1; and, FIG. 3 is a bottom view of the device shown in FIG. 1.

The broken line showing of a fastening element is for illustrative purposes only and forms no part of the claimed design.
